UNITED STATES PATENT OFFICE.

WOLF KRITCHEVSKY AND HAROLD C. PRUTSMAN, OF CHICAGO, ILLINOIS, ASSIGNEES
TO WILLIAM CITRON, TRUSTEE, OF CHICAGO, ILLINOIS.

PROCESS OF DEODORIZING KEROSENE.

No Drawing.

Application filed July 2, 1924. Serial No. 723,649.

To all whom it may concern:

Be it known that we, WOLF KRITCHEVSKY and HAROLD C. PRUTSMAN, citizens of the United States, and residents of Chicago, in

5 the county of Cook and State of Illinois, have invented certain new and useful Improvements in Processes of Deodorizing Kerosene, of which the following is a specification.

10 This application is a continuation in part of our application, Serial No. 615,373, filed Jan. 27, 1923.

One of the objects of our invention is to so treat commercial kerosene or other 15 light hydrocarbon as to eliminate the characteristic odor thereof, whatever odor remaining being unobjectionable. Such a product is highly useful for many purposes, for which the hydrocarbon in its original 20 state is objectionable.

Another object is to produce the product as described by means of a process which may be economically carried out. By the 25 use of our process the volume of chemicals employed for securing the desired result is materially reduced over that required in any of the known processes.

According to our invention we effect the 30 desired result by simultaneously oxidizing and sulphonating the hydrocarbon by the use of chlorsulphonic acid, then purifying with a concentrated alkali, then finally treating with a colloidal substance.

In the practice of the invention we first 35 treat the kerosene or other hydrocarbon with approximately 1% by volume of chlorsulphonic acid. As a result of the chemical reaction the temperature is raised and then lowered and a sludge settles which is drawn off and the operation preferably repeated, depending upon the impurities in the kerosene. Thereafter the product is washed with water and then with a strong alkali such as sodium hydroxide. It is then washed 40 and the hydrocarbon is stirred for several hours with a colloidal substance such as

fuller's earth, Kieselguhr or charcoal, etc. Following the subsequent filtering the material is free from objectionable characteristic odors of the hydrocarbon.

Instead of chlorsulphonic acid, we may employ reagents which form that acid such as a mixture of fuming sulphuric acid and sodium chloride.

The quantity of chemicals employed is 55 relatively small and the process may be carried out at a reasonably low cost compared to the cost of processes heretofore known. While we have specified a definite proportion of acid we do not wish to be 60 limited exactly to that proportion as variations may be made without destroying the beneficial results.

The amount used depends upon the quantity of aromatic hydrocarbons and sulphur 65 derivatives in the aliphatic hydrocarbons.

We claim:

1. The method of deodorizing kerosene which consists in treating the same with chlorsulphonic acid, then washing, then 70 treating with an alkali, and then treating with a solid absorbent colloid.

2. The method of deodorizing kerosene which consists in treating the same with substantially 1% by volume of chlorsulphonic acid, removing the sludge, then 75 washing and treating with alkali, then washing and treating with a solid absorbent colloid.

3. The method of deodorizing kerosene 80 which consists in treating the same with substantially 1% by volume of chlorsulphonic acid, then removing the sludge and repeating the operation with a like amount of chlorsulphonic acid, then treating with 85 an alkali, and then with a solid absorbent colloid.

Signed at Chicago, Ill., this 16th day of June, 1924.

WOLF KRITCHEVSKY.
HAROLD C. PRUTSMAN.
